OBTURATOR OR VALVE

Ernest Mercier and Marcel Ehlinger, Paris, France, assignors, by mesne assignments, to Moore, Inc., Atlanta, Ga., a corporation of Georgia

Application June 19, 1945, Serial No. 609,390
In France September 12, 1942

Section 1, Public Law 690, August 8, 1946
Patent expires September 12, 1962

6 Claims. (Cl. 251—51)

1

The present invention relates to an obturator or valve structure applicable to piston machines in which the fluids are expanded or compressed.

The obturator essentially consists in a plane or curved metal blade or valve, of small thickness, perforated with a plurality of ports the number of which may be varied, this blade sliding with a reciprocating movement between cheek members perforated with ports identical to the ports in the blades, said cheek members constituting, upon registration of their ports with those of the blade, a series of convergent-divergent nozzles in the neck of which moves the blade, which nozzles are directly traversed by the fluid.

Such an obturator or valve offers, on the one hand, the advantage of allowing the passage of the fluids at very high speed with only a small loss of pressure owing to the shape of the nozzles and, on the other hand, the advantage of being capable of reciprocation at high frequency owing to the lightness of the movable part, that is, the blade and to the small amount of movement required for a given valve opening.

The invention can be applied to machines having a driving shaft, as well as to machines without a driving shaft, and to free piston machines.

The valve can be controlled by a crank, eccentric or cam in a conventional manner but in the case of machines without a crankshaft, in particular those having a high frequency of reciprocation, it may be advantageous to control it pneumatically.

Such pneumatic control may be accomplished by connecting the obturator or valve with a piston receiving, at suitable times owing to the functioning of appropriate distributors, a compressed gas alternately on one face and the other, which piston, after having been accelerated during the first part of its stroke by the compressed gas, is braked in the second part of its stroke by an oil brake.

Fig. 1 illustrates the obturator or valve construction in section.

Fig. 2 illustrates in plan view the movable part or blade of the valve.

Fig. 3 shows a modification of the blade of Fig. 2.

Figs. 4 and 5 show respectively in vertical section and in plan another modification of the obturator.

The obturator of Fig. 1 comprises a movable part or blade 16, constituted by a plate of small thickness perforated with a plurality of parallel slots 15 of small width relative to the total flow area of the valve. The blade or valve 16 moves between grids providing members 17, 18 having

2

the opposite surfaces thereof formed in continuous smooth outlines which are connected at least at one side of the valve by curved outlines to form rounded noses on the members 17, 18. These members separate passages of the same number as the slots 15, the grid 17 being on the inlet side and the grid 18 on the outlet side of the device with respect to flow of the fluid, for example, air. Blade 16 takes either the position indicated at the left in Fig. 1, which corresponds to opening for the passage of the fluid which can take place with a minimum loss of pressure owing to its direct passage through openings in the shape of nozzles, the outlines of members 17, 18 being continuous with the interior surface of the ports 15, or the position indicated at the right in Fig. 1, which corresponds to closing of the passage to stop flow of the fluid. The very light member 16 can be subjected to a great acceleration and to reversal of the direction of its movement without producing excessive stress in the valve structure or in the control. It is driven by the rod 19.

In the case in which the fluid flow passing through the obturator is large, the blade and the grid can be perforated with several rows of slots, as indicated in Fig. 3.

The obturator or valve according to the present invention can advantageously be constructed as shown in Figs. 4 and 5. The fixed grids of the valve are constituted by bars of profiled shape, such as 71 and 72, held at the respective sides of the valve between the two parts 73 and 74 acting as a frame. A plate perforated with slots such as the plate 16 of Fig. 1 may oscillate in the space shown in Fig. 4 between the bars 71 and 72 and between the frame parts 73, 74 with its surfaces in contact with the seats provided on these bars and parts, the ports in the plate being registerable with the passages provided between the bars when the plate is in a given position of its movement.

In the embodiments of Fig. 1 and Figs. 4 and 5 the members 17, 18 and the bars 71, 72 provide surfaces defining the respective flow passages between these members or bars which have substantially continuous smooth outlines in the direction transversely of the valve seat or seats. These outlines respectively are continuous with the outlines of the internal surfaces of the respective ports in the slide valve or blade when the slide valve is in a given position in which the ports thereof are in registration with the passages between the separating members or bars. These passages thus defined by the surfaces of the members or bars constitute continuous nozzles of varying cross sec-

tion through the means which provides the valve seat or seats and through the slide valve when this valve is in the given position. These passages may be provided as shown in the drawings at both sides of the slide valve.

The opposite surfaces of the respective passages at least at a given side of the slide valve diverge from each other substantially from the smallest cross section of the respective passages. Preferably the outlines defining each passage diverge at least at one side of the valve in smooth curves substantially from the valve seat. In a valve structure providing two seats cooperating with the respective opposite faces of the slide valve the spacing of these seats and the corresponding thickness of the valve may be so restricted and the seats may be so positioned with respect to the extent of the passages transversely of the seats that both these seats and both faces of the valves are disposed adjacent the smallest cross section of the passages.

As shown in the drawings the members or bars at least at one side of the slide valve at the ends thereof spaced along the passages from the slide valve are curved smoothly to connect the outlines of adjacent passages at opposite sides of the respective members or bars to form rounded noses on these ends of the members or bars. As shown in Fig. 1 preferably the members or bars providing the rounded noses are disposed at the inlet side of the valve with respect to the flow of the fluid therethrough.

What we claim as our invention and desire to secure by Letters Patent is:

1. In a valve structure, a slide valve having a plurality of ports therein spaced in the direction parallel to the sliding movement of said valve, and means providing valve seats cooperating with opposite faces of said slide valve for sliding movement of said valve in contact with and relative to said seats and providing members at both sides of said valve separating a plurality of passages respectively registerable simultaneously with said ports in said slide valve upon sliding movement of said valve to a given position relative to said seats, the shape and area of the cross section of the respective passages at said seats being substantially the same as the shape and area of the cross section of the ports registerable with said respective passages, said members at least at a given side of said valve each having a substantial extent in the direction transversely of said valve seats and having the surfaces thereof formed in substantially continuous smooth outlines in said direction, said outlines respectively being continuous with the outlines of the internal surfaces of the respective ports to form continuous nozzles of varying cross section along the respective passages through said means providing said valve seats and through said slide valve when said valve is in said given position, said outlines of the respective members which form opposite surfaces of the respective passages diverging from each other at least at said given side of said slide valve substantially from the smallest cross section of said passages, said members at the ends thereof spaced along said passages from said slide valve at least at said given side of said valve being curved smoothly to connect the outlines of adjacent passages at opposite sides of the respective members to form rounded noses at said ends of said members.

2. In a valve structure, a slide valve having a plurality of ports therein spaced in the direction parallel to the sliding movement of said valve, and

means providing valve seats respectively cooperating with opposite faces of said slide valve for sliding movement of said valve in contact with and relative to said seats and providing members at both sides of said valve separating a plurality of passages respectively registerable simultaneously with said ports in said slide valve upon sliding movement of said valve to a given position relative to said seats, the shape and area of the cross section of the respective passages at said seats being substantially the same as the shape and area of the cross section of the ports registerable with said respective passages, said members each having a substantial extent in the direction transversely of said valve seats and having the surfaces thereof formed in substantially continuous smooth outlines in said direction, said outlines respectively being continuous with the outlines of the internal surfaces of the respective ports to form continuous nozzles of varying cross section along the respective passages through said means providing said valve seats and through said slide valve when said valve is in said given position, said outlines of the respective members which form opposite surfaces of the respective passages diverging from each other at least at a given side of said slide valve substantially from the smallest cross section of said passages, said members at the ends thereof spaced along said passages from said slide valve at least at said given side of said slide valve being curved smoothly to connect the outlines of adjacent passages at opposite sides of the respective members to form rounded noses on said members at said ends of said members.

3. In a valve structure as defined in claim 2, the space between said seats and the corresponding thickness of said valve between said opposite faces thereof being so restricted and said seats being so positioned with respect to said extent of said members transverse to said seats that both said faces and the respective seats are disposed adjacent said smallest cross section of said passages.

4. In a valve structure as defined in claim 3, said outlines diverging from said seats at both sides of said valves.

5. In a valve structure as defined in claim 1, said ports in said valve being of elongated form arranged with their lengths parallel to each other in the plane of said seat and spaced transversely of said lengths in the direction parallel to said movement of said valve.

6. In a valve structure as defined in claim 2, means providing a frame, said passage separating members being provided by a plurality of adjacently positioned bars supported in said frame in spaced relation in the direction of movement of said valve, said frame and said bars providing said valve seats, adjacent bars at each side of said valve being disposed and being formed to provide said passages between said bars with a cross section the shape and area of which at the respective seats is substantially the same as the shape and area of the cross section of said ports in said valve, said bars at least at one side of said valve providing at opposite sides thereof surfaces of substantially continuous smooth outlines, said outlines extending transversely of and converging in the direction from said valve in a plane perpendicular to said seats parallel to the direction of sliding movement of said valve to define the surfaces of adjacent passages, said outlines including the outline of the internal surfaces of said ports to form said continuous nozzles of varying

5

cross section through said means providing said valve seats and through said valve, said outlines at said opposite sides of the respective bars being connected by curved outlines at the ends of said bars spaced from said valve seats to form rounded noses at said ends of said bars.
